UNITED STATES PATENT OFFICE.

JOHNSTON WAGNER, OF MOORHEAD, MINNESOTA.

ENDLESS CARRIER FOR HARVESTERS.

SPECIFICATION forming part of Letters Patent No. 293,383, dated February 12, 1884.

Application filed October 3, 1883. (No model.)

To all whom it may concern:

Be it known that I, JOHNSTON WAGNER, a citizen of the United States, residing at Moorhead, in the county of Clay and State of Minnesota, have invented certain new and useful Improvements in Endless Carriers for Harvesters and other Machines, of which the following is a specification, reference being had therein to the accompanying drawings.

10 My invention relates to that class of endless carriers consisting of an endless apron supported on rollers or drums arranged at opposite ends of a frame, which may be placed horizontally or in an inclined position, accordingly as it may be desirable to transport the material to be conveyed horizontally or to elevate the same; and the object of my invention is to provide simple and efficient means for properly tightening the carrier-apron by simultaneously adjusting both of the journal-bearings of one of the supporting drums or rollers for the said carrier-apron, thus quickly and easily effecting the adjustment, and at the same time keeping the rollers parallel to each other.

25 In the accompanying drawings, Figure 1 is a plan view, partly in section, of an endless carrier embodying my invention. Fig. 2 is a sectional view of the same on the line 22, Fig. 30 1; and Fig. 3 is a side view.

30 A A are the stationary or fixed side pieces of the carrier-frame, in which one of the supporting drums or rollers B is journaled, the power for moving the carrier-apron C being preferably applied to the shaft of the said roller by means of a gear or sprocket wheel or a sheave secured to said shaft. The side pieces, A, are recessed on their inner faces for the reception of plates D, which latter are provided 35 at their outer ends with blocks d, having bearings for the adjustable supporting drum or roller B' for the carrier-apron. The plates D are preferably of metal, and the bearing-blocks d may be formed integral therewith or secured 40 thereto in any suitable manner. The plates D are each provided with inner slots, d', and outer slots, d'', one side of each of the outer slots being formed into teeth, constituting a rack, d''. As the slots d' and d'' are both 45 closed—or, in other words, are bounded on their opposite sides by the material compos-

ing the plates D—said slots are adapted to serve as guideways, as will presently be indicated. Arranged within the inner slots, d', of the plates D are guiding pins or bolts a, entering the side pieces, A, of the carrier-frame, said pins or bolts being preferably screw-threaded, so that they will be securely held in said side pieces. These pins or bolts a, one or more of which may be placed in each of the 55 slots d, serve, in connection with said slots, to assist in guiding the plates D on the side pieces, A, thus preserving the alignment of said plates with said side pieces as the former are moved outward in tightening the carrier- 60 apron.

65 F is the tightening-shaft for the endless carrier-apron, said shaft being journaled in the side pieces, A. Formed integral with or secured to the shaft F are two pinions, f, arranged within the outer inclosed slots, d'', of the plates D, said pinions being preferably of such size that they can just barely turn freely within said slots without binding, thereby assisting in preserving the alignment of the plates 70 D with the side pieces, A. One end of the shaft F projects through one of the side pieces, A, and a ratchet-wheel, f', is secured to said shaft outside of and adjacent to the side piece, and to the latter a pawl, f'', is pivoted in such 75 position as to engage with said ratchet-wheel and prevent its backward rotation after the shaft F has been adjusted, thus holding the plates D and the adjustable supporting drum or roller B' securely in position. The projecting end of the shaft F is squared for the reception of a key or wrench, G, by means of which 80 said shaft may be turned when desired. It will be understood that the pinions f on the shaft F are both just alike, as are also the racks 85 d'' on the plates D, so that when the shaft F is turned both of the plates D will be moved an equal distance, thus simultaneously adjusting 90 both of the bearings for the adjustable supporting-roller B', which latter, whatever its 95 position of adjustment, will always be parallel with the roller B. Thus the carrier-apron C will at all times run evenly on the said rollers, and said apron may be quickly and easily tightened or slackened as circumstances may 100 require.

I am aware that it is not new to adjust both

of the bearings of one of the supporting-rollers of an endless carrier-apron simultaneously, and I do not, therefore, wish to be understood as broadly claiming means for effecting this 5 result; but

What I do claim, and desire to secure by Letters Patent, is—

1. In an endless carrier, the combination, with the side pieces of the frame, of a drum or roller journaled in said side pieces, two adjustable plates, each provided with inner and outer inclosed slots, the outer slots each having a rack on one side, pins or bolts fixed to said side pieces and arranged in the said inner 15 slots, a drum or roller journaled in the outer ends of said plates, a shaft journaled in said side pieces, two pinions fixed to said shaft and arranged in said outer slots in engagement

with racks, and means for securing said plates in position after adjustment, substantially as 20 hereinbefore set forth.

2. The combination, with the recessed side pieces, A A, of the drum or roller B, the plates D D, provided with bearing-blocks d , inner slots, d' , and outer slots, d'' , the latter having 25 racks d'' , the drum or roller B', the pins a a , the shaft F, the pinions f f , the ratchet-wheel f' , and the pawl f'' , substantially as hereinbefore set forth.

In testimony whereof I affix my signature in 30 presence of two witnesses.

JOHNSTON WAGNER.
